PROCESS OF MAKING A FOOD DISPLAY COVER

Arthur E. Rouse, Indianapolis, Ind., assignor, by
mesne assignments, to Food Display Cover
Company, Inc., Indianapolis, Ind., a corpora-
tion of Indiana

Application October 2, 1936, Serial No. 103,714

2 Claims. (Cl. 93—1)

This invention relates to a method of producing a translucent, sanitary display cover, light in weight, to tastily present and display in a sanitary manner foods, and the like, and the display 5 per se.

The chief object of this invention is to produce a translucent and preferably transparent display cover of the desired height and outline, which is exceedingly light in weight, thereby 10 distinguishing from glass covers and which is non-fragile, similarly distinguishing therefrom, and which is relatively non-inflammable and which is of relatively low combustibility, thereby 15 distinguishing from certain cellulose covers of materials of the character known as "Cellophane", which are highly inflammable, and which novel covers are relatively non-inflammable, thereby further distinguishing from "Cellophane" 20 covers.

20 The chief feature of the invention consists in the method of fabrication, whereby there is produced a sanitary display cover of the character briefly set forth.

25 Another feature of the invention consists in the construction of the sanitary cover.

As previously set forth, certain transparent or translucent materials, such as glass and/or "Cellophane" have certain inherent objections to their use as a sanitary, translucent or transparent 30 display cover.

The present invention is directed toward the application of sheet material of the character hereinbefore briefly mentioned, to a metallic frame usually of wire, and provided with a handle, if, as and when desired. The material in question is an acetate sheet, preferably about .003" in thickness. It is transparent, flexible, stretches well under pressure, is of relatively 35 low inflammability, and when ignited will burn very slowly with substantially little or no flame. For specific purposes, sheeting of slightly less thickness or greater thickness than that specified 40 may be employed.

45 The frame broadly speaking is of open-work character, having ribs, or the like, and a peripheral border. Supplementary frame members may also be provided, the cover conforming generally to the conformation, as determined by the frame.

50 In the preferred method of cover production, there is first provided the open-work frame without a handle. There is then superimposed thereon the acetate sheeting of the desired size and outline. If a single sheet be employed, it is then 55 made to conform generally to the frame work

and is cut and trimmed so to do, leaving sufficient marginal edges for lapping purposes. The frame work may be of lacquered wire, aluminum wire, or chromium plated wire. The sheeting may be clear and transparent or may be suitably colored 5 and, therefore, translucent.

The handle may be of any desired shape or outline and of wood, composition, metal, porcelain or glass, it is suitable anchored to the frame 10 work and preferably after the sheeting is applied thereto and tautened thereon.

After initial application of the sheeting material to the cover, the several joints are sealed by applying acetone to the lapping surfaces. This 15 presupposes an initial stretching operation. The lap joint produced thereby is of appreciable width. Certain portions of the frame are partially enveloped by the sheet material. Other portions of the frame are entirely enveloped by 20 the sheet material, the latter usually being the peripheral portion thereof.

After having sealed the sheet material to the frame, the display cover presents a rather crude and wrinkled appearance, there being certain 25 bulges therein due to excess material. The cover is then subjected to heat by positioning the same in an oven or subjecting it to heat derived from an open flame, care, of course, in the latter instance being exercised to prevent direct contact 30 of the sheet material of the cover with the flame. It has been determined that a suitable temperature is about 200° F. and the approximate maximum temperature is 250° F. This operation has 35 been termed "thawing out" or "tempering" and serves to take up the slackness, looseness, bulges, and the like, in the cover so that the resulting sheet material on the frame is tautened and presents a highly pleasing finished appearance. Following this operation if the handle has not been 40 previously applied to the covered frame, the same is then applied thereto.

When a single sheet is used, the mounting of the handle naturally perforates the sheet at the point of handle mounting.

By way of example and in further explanation 45 of the invention, reference will be had to one form of cover and the same is illustrative of the broad invention.

The full nature of the invention will be understood from the accompanying drawing and the following description and claims:

In the drawing Fig. 1 is a perspective view of a completed cover.

Fig. 2 is a central sectional view thereof.

Fig. 3 is a transverse, sectional view through 55

a corner portion of the cover immediately above the bottom portion thereof.

Fig. 4 is a plan view of a portion of the frame work at the handle mounting portion and one form of frame work.

Fig. 5 is a perspective view of the stretch or rupture test for the material.

In the drawing 10 indicates a border wire. 11 indicates a supplementary border wire. 12 indicates diagonal ribs having the downwardly and outwardly directed portions 13. As shown in Fig. 4 these diagonal ribs may be centrally discontinued although rigidly connected. Intermediate and radially projecting ribs 14 similarly are provided with downwardly and outwardly directed extensions 15, all of the radial ribs being connected to the auxiliary peripheral frame element 11 and the peripheral frame element 10 in any suitable or desirable manner.

Herein, for convenience only, the display cover is illustrated as of rectangular outline. It may be polygonal or circular. Also, the open type frame work, in the case of the quadrilaterally outlined figure, may be provided with a plurality of wicket or arc shaped members 14-15 in parallel relation and the supplementary peripheral member 11 may or may not be used, as desired.

Reference will now be had to Fig. 4. In this figure the transverse ribs 14 and the diagonal ribs 12 all terminate short of meeting engagement with their aligned rib and all are flattened and welded, or the like, to a central member in the form of a washer 16 having the central opening 17.

The acetate sheet A having the characteristics before mentioned, may be gripped in two hands, B and C, see Fig. 5, and pressed downwardly upon a blunt support such as a pencil D, suitably supported as being held in the hand E. This sheet 35 will stretch without rupture to the extent disclosed in Fig. 5. This test indicates the sheet material may have considerable thumb or finger pressure applied to it when applied to the frame in cover formation without rupture. Of course, a pointed instrument will pierce the material.

The invention will now be described as embodying a single sheet applied to the open type frame work, since this is the most expeditious manner of covering the frame, but the invention 50 is not necessarily restricted thereto.

The sheet 18 is superimposed upon the cover and drawn down, portions of the sheet being cut away so that the same form the sides F and G of the cover. It will be noted the surplus corner material in the sheet is removed up to a point indicated by the numeral 19 in Figs. 1 and 2. The material is cut so as to provide lapping flaps 20 along the sides and bottom lapping flaps 21. The material after initial stretching or smoothing out, 55 then has applied to the portions to be lapped a thin coating of acetone and pressure is applied to form the lapped joints in the sides at the corners which partially embrace the frame and the lapped joints at the bottom of the cover which 60 completely embrace the peripheral portion of the frame.

Preferably, the sheet is cut to the approximate requirements and then is trimmed as desired or required. It will be observed that the lapped joints are of appreciable width. This is to insure the positive anchorage necessary in the subsequent operation. At this point or following the operation now to be described, the handle may be applied to the structure.

The operation referred to is the tempering or "thawing out" operation. When the connections 10 have sufficiently solidified or set, the cover is subjected to heat which tautens the cover and removes all irregularities in the sheet material and stretches the cover upon the frame. There is quite a bit of tension in the various panels of the 15 cover defined by the frame members. Wherefore, the joint anchorages specified hereinbefore must be of the character set forth. Following the tempering operation or preceding the same, as desired, the handle is mounted on the cover 20 structure. The handle herein is illustrated as a glass knob 23 having a longitudinal coaxial opening extending therethrough which receives in countersunk relation the body and head of an elongated screw bolt 24. The screw bolt 24 supports a washer 25 below the flattened ends of the 25 radially directed ribs and bearing thereon in clamping relation is the nut 26. Thus the handle is rigidly secured to the cover and the cover is a completed structure.

While the invention has been described in great detail in the drawing and description, respectively, the same is to be considered as illustrative and not restrictive in character.

The several modifications mentioned herein as 35 well as others which will readily suggest themselves to persons skilled in this art, are all considered to be within the broad scope of the invention, reference being had to the appended claims.

The invention claimed is:

1. The method of making a sanitary cover, comprising an open frame, consisting in applying to said frame a sheet of material capable of being shrunk below its normal size by heat and of a size 45 initially greater than the area of said frame, engaging the edges of said sheet around the perimeter of the frame and cementing the said edges thereto, and finally subjecting the frame and its sheet to a temperature sufficient only to shrink 50 the sheet evenly in all directions without distortion of the frame.

2. The method of producing a sanitary cover including an open metallic frame having an anchoring post disposed inwardly from its edges, consisting in applying to said frame a sheet of material capable of being shrunk below its normal size by heat and of a size initially greater than the area of the frame, anchoring said sheet to said post, engaging the edges of said sheet around the perimeter of the frame and cementing said edges thereto, and finally subjecting the frame and its sheet to a temperature sufficient only to shrink 55 the sheet evenly in all directions without distortion of the frame.

ARTHUR E. ROUSE.
